UNITED STATES PATENT OFFICE

2,477,746

PORTABLE ELECTRIC LAMP CONTROLLER

John McKeon Huddleston, Jr., Shreveport La.

Application February 21, 1946; Serial No. 649,366

3 Claims. (Cl. 201—48)

1

This invention relates to a portable electric lamp. More particularly it has to do with such lamps of the type which is capable of emitting illumination of variable intensity.

An object of the invention is to provide an electric lamp wherein the intensity of the illumination emitted from the light source may be varied.

Another object of the invention is to provide an electric lamp which includes a means for adjustably controlling the emitted illumination.

A further object of the invention is to provide an electric lamp in which the emitted illumination may be increased or decreased within pre-scribed limits.

Other objects and advantages will become apparent from the following description.

An embodiment of the invention is illustrated by way of example in the accompanying drawing wherein:

Figure 1 is a plan view with parts in section and parts broken away, of the base of the electric lamp of the present invention.

Figure 2 is a side elevational view, with parts in section and parts broken away, of the electric lamp base of the present invention.

Figure 3 is a diagrammatic view of the electric circuit.

Figure 4 is a side elevational view of the electric lamp.

With continued reference to the drawing, the improved portable lamp comprises, in general, a base 10, a standard 11, and an illuminating or light unit 12, as shown in operative assembly in Figure 4.

The light unit includes a conventional bulb socket mounted on the upper end of standard 11, a conventional light bulb 8 in the socket, and a shade 13 supported by the standard and surrounding the light bulb. As illustrated in Figure 2, the standard 11 is tubular, providing a channel for a pair of insulated wires 14 and 15, electrically connected with the bulb socket, not illustrated. As the above-described construction may be entirely conventional, it has not been illustrated in detail and a further description is not believed necessary for the purposes of the present disclosure.

The lamp base 10 has a flat, circular bottom plate 16 having a central aperture 17 and an annular groove 18 in the upper surface thereof, said aperture having a counterbore 19 at its upper end.

A rheostat housing, generally indicated at 20, has an annular base flange 21 of tapered cross-sectional shape, a transverse wall 22 provided

with a central aperture, and a cylindrical wall 23 of less diameter than the base flange 21 extending upwardly from the transverse wall 22 substantially concentric therewith.

The lower edge of the base flange 21 of the rheostat housing is secured in the annular groove 18 of the bottom plate, supporting the transverse wall 22 above and substantially parallel to the upper surface of the bottom plate, and the lower, externally screw-threaded end of tubular standard 11 extends through the central aperture in transverse wall 22 and is secured to the transverse wall by a pair of jamb nuts 24 threaded onto the standard and disposed one at each side of the transverse wall. The lower end of the standard is received in the counterbore 19 of bottom plate 16.

A circular body 25, of electrical insulating material is disposed within the cylindrical wall 23 of housing 20 and rests upon transverse wall 22. This body 25 has a central aperture which receives the corresponding portion of tubular standard 11, and an annular groove 26 of substantially semi-circular cross-sectional shape, in its cone-shaped upper surface. This body is also provided with a vertical opening 27 receiving a conductor trip 28, the purpose of which will be later explained.

An annular rheostat, generally indicated at 30, has a lower edge of generally semi-circular cross-sectional shape received in groove 26 to operatively mount the rheostat on body 25 in a manner in which it is electrically insulated both from the rheostat housing 20 and the standard 11. The rheostat has an annular core 31 of electrical insulating material and an electrical resistance coil 32 wound upon the core in conventional manner.

One end of coil 32 is electrically connected to a switch contact arm 33 which is rigidly secured to the rheostat and extends outwardly through an opening 34 in wall 23 of the rheostat housing.

A ring 35 of electrical insulating material is rotatably mounted surrounding wall 23 near the top thereof by a pair of spacer rings 36 and 37 secured to the outer surface of wall 23, one above and one below ring 35. This ring 35 is provided with a recess 38 into which the outer end of contact arm 33 extends and in which a contact clip 39 is mounted for operative, electrically-conductive engagement with arm 33. Clip 39 is moved into and out of engagement with arm 33 by partial rotation of ring 35; rotational movements of which are limited by contact of arm 33 with clip 39 and with the end of recess 38 opposite clip 39. Clip 39 is electrically connected to wire 15

so that the clip and arm 33 provide an on-and-off switch between the lamp bulb socket and the rheostat.

A ring 40, preferably of substantially the same diameter as ring 35, is fixedly secured to the cylindrical wall 23 of the rheostat housing between spacer ring 37 and a spacer ring 41 which rests upon the upper surface of transverse wall 22 outside of cylindrical wall 23, and a ring 42 is secured in surrounding relationship to base flange 21 at the upper end thereof. Rings 40 and 42 provide convenient means for holding the main part of the lamp base stationary while movable components thereof are manually rotated.

Double spring rheostat arm 43 is apertured to receive standard 11 and carries at one end a contact button 44 which rides on the upper edge of rheostat 30 in electrical contact with coil 32. The upper end of conductor strip 48 surrounds standard 11 and rests on the upper surface of body 25 surrounding the standard. This upper end of strip 28 makes electrical contact with rheostat arm 43 and the lower end is connected to a lead-in wire 45. With this arrangement an electrical circuit is provided through wire 45, strip 28, arm 43, rheostat 30, contact arm 33, clip 39, wire 15, the light bulb socket and bulb, and lead-in wire 14 which parallels wire 45, to energize the lamp bulb when clip 39 is closed with contact arm 33.

A ring or disc 46, preferably of the same diameter as rings 35 and 40, is provided with a central aperture receiving standard 11 and is disposed immediately above the annular wall 23 of the rheostat housing. A sleeve 47, of electrical insulating material, surrounds standard 11 within the opening in disc 46 and a two-part cylindrical bearing member 48 surrounds sleeve 47 within the disc opening. The outer part of bearing member 48 is secured to disc 46 and to rheostat arm 43 to provide a driving connection between the disc and the arm so that the arm will be moved around rheostat 30 when disc 46 is rotated.

With clip 39 closed with contact arm 33, rotation of disc 46 will vary the current supplied to the lamp bulb in accordance with the well-known operation of rheostats, and thereby vary the intensity of illumination provided.

In operation of the electric lamp as described, for lighting the lamp the operator rotates the ring member 35 until the contact clip 39 is brought into contacting engagement with the switch arm 33. This closes the circuit and results in the lighting of the light source 8. To vary the emitted illumination, the operator then rotates the disc 46 in the desired direction and to the required degree. By this latter action the intensity of the emitted illumination is increased or decreased to the desired amount. To shut off the lamp, the operator merely rotates the ring member in the opposite direction until the contact clip 39 and the switch arm 33 disengage. The previous setting of the disc 46 may be retained for a subsequent illumination of the lamp or it may be adjusted after the lamp is again relighted.

I claim:

1. A rheostat and switch assembly for an electric lamp comprising a housing including a cylindrical wall and a bottom plate at one end of said cylindrical wall, a tubular standard secured at its lower end to said bottom plate substantially centrally of the latter and extending concentrically through said cylindrical housing wall, a rheostat mounted in said housing surrounding said stand-

ard and insulated therefrom, a contact arm mounted on said rheostat and electrically connected therewith, said contact arm projecting outwardly of said housing, a ring surrounding said housing and having a recess therein receiving the outer end of said contact arm, a contact clip mounted on said ring in said recess and movable into and out of electrically conductive engagement with said arm by rotational movements of said ring on said housing, a rheostat arm journaled on said standard and having its outer end in electrically conductive contact with said rheostat, and a disc journaled on said standard immediately above said housing and drivingly connected with said rheostat arm.

2. A rheostat and switch assembly for an electric lamp comprising a housing including a generally cylindrical wall and a bottom plate at one end of said wall, a standard secured at its lower end to said bottom plate substantially centrally of the latter and extending co-axially through said cylindrical housing wall, an annular rheostat mounted in said housing and insulated therefrom, said rheostat concentrically surrounding said standard, a rheostat arm mounted on said standard, a switch electrically connected with said rheostat, a manually rotatable ring surrounding said housing and mounted thereon operatively engaging said switch, and a manually rotatable disc journaled on said standard and drivingly connected with said rheostat arm.

3. A rheostat and switch assembly for an electric lamp comprising a housing including a substantially cylindrical wall and a bottom wall joined to one end of said cylindrical wall and engageable with the lamp base, a standard secured to said bottom wall substantially at the center of the latter and extending concentrically through said substantially cylindrical housing wall, a rheostat including an annular body of insulating material in said housing surrounding said standard and resting upon said bottom wall, a resistance winding on said body, a rheostat arm rotatably mounted at one end on said standard and overlying said resistance winding, and a contact button carried by said arm and bearing upon said winding, a disc journaled at its center on said standard immediately above said housing, means drivingly connecting said disc to said rheostat arm for manual adjustment of said rheostat, a contact arm connected to said rheostat winding and projecting outwardly of said housing, a ring mounted on said housing in surrounding relationship thereto for limited freedom of rotational movement relative to said housing, said ring having a recess therein receiving said contact arm, and a contact clip mounted on said ring within said recess, said arm and clip constituting on and off switch components for said assembly.
